 2 Claims. (Cl. 91—5)

This invention relates to a pneumatic sawtooth oscillator, and, more particularly, to a pneumatic system capable of inflating a balloon rapidly and deflating it slowly so that the variation of the balloon volume with time has a sawtooth waveform.

It is an object of this invention to provide a unique pneumatic system wherein a balloon is cyclically inflated and deflated to provide an output characterized by a sawtooth waveform. Another object is to provide a system of the character described in the object immediately preceding wherein the balloon is inflated from an isolated tank of small volume charged to high pressure, whereby danger of balloon bursting is avoided.

Still another object of the invention is to provide a pneumatic system capable of cyclically inflating and deflating a balloon having only a negligible wall tension when inflated, in conjunction with a self-actuated four-way, two-position valve.

Yet another object is to provide a pneumatic system providing a sawtooth waveform output wherein flow constriction means are provided for varying both the slope and the period of the waveform. Other objects and advantages of the invention may be seen in the details of construction and operation set down in this specification.

The invention is described in conjunction with the accompanying drawing, in which

FIG. 1 is a schematic representation of the inventive system;

FIG. 2 is a schematic representation of a simplified version of the system for a mathematical derivation appearing hereinafter; and FIG. 3 is a graph of the variation of pressure (P) at the balloon port as a function of time (T).

Numerous occasions arise in pneumatic systems applications where it is necessary to design an oscillator having a sawtooth output waveform, i.e., driving pistons which must oscillate a load back and forth such as in an automatic production line. If rapid cycling or steep wave fronts are not necessary, the sawtooth waveform can be formed by means of mechanical-linkage feedback to a conventional cam-stem four-way valve from the piston of a standard cylinder fitted with a controlled orifice to slow the return stroke. However, such a method gives a system too complex, heavy, noisy and slow for many applications. In contrast to this, the rapid inflation-slow deflation means disclosed herein provides a system uniquely meeting the requirements of a high speed, simple, lightweight system.

Such a system is seen in FIG. 1, wherein the numeral 10 refers to a four-way valve coupled to a pressure source (of say 90 p.s.i.g.) as at 11 and to a suction source as at 12. The valve 10 is equipped with a spool 13 (shown in chain line), biased downwardly by means of a spring schematically represented at 14. The spool 13 is adapted for two-position operation, with the flow passages in one position seen in solid line as at 15 and 16, while those in the alternative position are shown in dotted line as at 17 and 18.

The other elements of the system include a storage tank 19 and an inflatable balloon 20. A first conduit 21 couples the valve 10 to the tank 19, the first conduit 21 being equipped with a check valve 22. A second conduit 23 couples the valve 10 to the balloon 20 at the balloon port

20a and is equipped with a flow constriction device generally designated 24. The device 24 is made up of a check valve 25 and a throttle valve for variable constriction 26.

5 A third conduit 27 couples the first conduit 21 to the pilot end of the valve 10 as at 28 for overcoming the bias of spring 14. The third conduit 27 is equipped with a flow control device generally designated 29, made up of a check valve 30 and a throttle valve 31, similar to the arrangement designated 24.

The flow control devices 24 and 29 may be Modernair Valves No. 100, obtainable from Schrader Air Control Products Co., of New York city. Also, the valve 10 is obtainable from Schrader Air Control Products Co., being a four-way, single pilot-operated, two-position valve.

10 In FIG. 1, the spool 13 is in its lower position and, as such, connects the pressure source (as at 11) to the tank 19 and via the third conduit 27 to the pilot port 28. This results in delivering pressure fluid to the tank 19 and relatively slowly delivering pressure fluid to the pilot port 28. Depending upon the bias in the spring 14, the volume of the piping system and the setting of the throttle valve 31, a time elapses until the pressure built up at pilot port 28 is sufficient to shift the spool to its upper position.

15 20 Thus the slope and period of the sawtooth waveform of FIG. 3 may be varied. In FIG. 3, the steeper slope line is seen to be dotted corresponding to the spool position coupling the tank with the balloon via the dotted passage 18. During the time of this pressure build-up in 25 the pilot port 28, the balloon 20 is being deflated through the throttle valve 26 by the suction source 12.

20 30 As soon as the spool 13 has shifted to the upper position, the tank 19 is in direct communication with the balloon 20 (via the check valve 25) to insure rapid inflation of the balloon. Meanwhile, via passage 17, the suction source 12 is in communication with the third conduit 27 to reduce the pressure at the pilot port 28, permitting the spring 14 to return the spool 13 to its lower position.

35 35 The device shown in FIGURE 1 overcomes the possibility of bursting, which is characteristic of any conventional constant pressure source for inflating the balloon. Any such source requires a valve which could accidentally stick open, and if this occurred even for a slight time, the balloon would burst. Since it is quantity rather than pressure which is desired in the balloon, this can be avoided by inflating the balloon from an isolated tank of small volume, charged to a relatively high pressure. FIG. 2 shows a sketch of the problem, and the mathematical derivation of the required tank volume in terms of charging pressure, atmospheric pressure, and the desired final balloon volume is set forth below.

Derivation

40 40 In FIG. 2, the portion of the system to the left of the valve D is designated 32, and this includes a rigid tank and pipe having a volume V_T , an initial pressure p_T , and a final pressure p .

The valve D is initially closed, and to the right of the 45 45 valve is provided a rigid pipe 33 which has a volume V_p and an initial pressure p_A . The numeral 20 designates the balloon (shown in deflated condition) which has an initial volume of 0, a final volume of V , and a final pressure p .

50 50 In terms of absolute (gauge plus atmospheric) pressures, the following equation applies:

$$p_T V_T + p_A V_p = (V_T + V_p + V)p \quad (1)$$

If the balloon wall tension remains negligible after inflation, the final pressure p is equal to atmospheric pressure p_A , so that Equation (1) becomes:

$$p_T V_T + p_A V_p = (V_T + V_p + V)p_A \quad (2)$$

Therefore, the pre-valve tank volume required to produce a given balloon volume is:

$$V_T = \frac{p_A}{p_T - p_A} V \quad (3)$$

From the foregoing, it is evident from the resultant formula that a high charging pressure is necessary not only to give a rapid inflation through the valve, but also to avoid an excessively large tank volume.

For rapidly inflating the balloon and slowly deflating the same in a cyclic, sawtooth wave form manner, the valve 10 in FIG. 1 functions automatically to perform the following sequential operations:

(a) Charging the tank 19 from a high pressure source while the balloon 20 is being slowly deflated by connection to low pressure suction;

(b) Isolating the tank from the high pressure source and the balloon from the low pressure suction;

(c) Rapidly inflating the balloon from the charged tank; and

(d) Successively repeating the sequence of three events.

The relatively simple pilot-operated four-way valve performs this automatic operation simply and reliably in that all ports are closed during the transition from one spool to the other. Oscillation frequencies of 0.1 to 10 cycles per second are realizable with the design indicated.

The spool of the four-way valve will change position when the pressure at the pilot port 28 exceeds a certain threshold value based upon the bias of the spring 14. The delay time during which the spool 13 remains at its normal position is thus a function of the spool threshold pressure, the adjustable flow resistance in the flow control device 29, and the small volume-trap for the air between the four-way valve spool 13 and the flow control device 29. As soon as the spool 13 of the four-way valve 10 changes position, further flow from the high pressure source is blocked, the suction pressure is removed from the balloon and applied to the flow control device 29, the tank quickly inflates the balloon, and the four-way valve spool 13 returns to its normal position slightly later (due to spool inertia and drag).

The cycle time of the oscillation may be varied by adjusting the orifice in the flow control device 29 (as at 31). Very slow oscillations may be achieved by increasing the volume of air trapped between the four-way valve spool 13 and the flow control device 29. The quantity of air delivered to the balloon at the end of each cycle can be varied by adjusting the volume of the tank (which may take the form of a cylinder with its adjustably-fixed piston). The highest attainable oscillation frequency is a function of the minimum drag and inertia of the four-way valve control spool and the lowest practical flow resistance of the valve ports in connecting lines.

The balloon referred to in the specific description is used only as an example, and may be replaced by any other expandable chamber such as a cylinder and piston or the pilot port of another pneumatic or hydraulic valve.

While in the foregoing specification a detailed description of an embodiment of the invention has been set down for the purpose of illustration, many variations in the details herein given may be made by those skilled in the art without departing from the spirit and scope of the invention.

I claim:

1. A pneumatic sawtooth oscillator, comprising a four-way valve comprising a casing, a two-position spool in said casing, spring means in said casing biasing said spool to one position, and port means located in said casing for pneumatically overcoming the bias of said spring means, a source of pressure fluid coupled to said valve, a pressure fluid tank, a first conduit coupling said valve and tank for flow of pressure fluid only from said source to said tank and only in said one position of said spool, a second conduit coupling said first conduit with said port means, a suction source also coupled to said valve, a port-equipped balloon inflatable by expanding pressure fluid from said tank, and a third conduit coupling said valve and said balloon for flow of pressure fluid from said tank to said balloon only in the other position of said spool, said spool in said one position coupling said balloon to said suction source, and flow constriction means in said second and third conduits operative to regulate the flow therein when said spool is in said one position.

2. A pneumatic sawtooth oscillator, comprising a four-way valve comprising a casing, a two-position spool in said casing, spring means in said casing biasing said spool to one position, and port means located in said casing for pneumatically overcoming the bias of said spring means, a source of pressure fluid coupled to said valve, a pressure fluid tank, a first conduit coupling said valve and tank for flow of pressure fluid only from said source to said tank and only in said one position of said spool, a second conduit coupling said first conduit with said port means, expandable chamber means inflatable by expanded pressure fluid from said tank, a third conduit coupling said valve and expandable chamber means for flow of pressure fluid from said tank to said expandable chamber means only in the other position of said spool, a suction source also coupled to said valve, said spool in said one position coupling said expandable chamber means to said suction source, and flow constriction means in said second and third conduits operative to regulate the flow therein when said spool is in said one position.
